Primary Examiner—Terry A. Wallace

[57] **CLAIM**

The ornamental design for a water draining coaster, as shown and described.

DESCRIPTION

FIG. 1 is a perspective view of a water draining coaster showing my new design;

FIG. 2 is a cross-section view thereof taken along line 2—2 of FIG. 1;

FIG. 3 is a top plan view of the drain plate portion, the opposite side being a mirror image except for a one half of an inch diameter by sixteenth of an inch deep centered indentation;

FIG. 4 is a top plan view of the sponge portion, the opposite side being a mirror image;

FIG. 5 is a top plan of the base portion;

FIG. 6 is a bottom plan view thereof;

FIG. 7 is a perspective view of an alternate embodiment of FIG. 1;

FIG. 8 is a top plan view of the drain plate portion, the opposite side being a mirror image except for a one half of an inch square by sixteenth of an inch deep centered indentation;

FIG. 9 is a top plan view of the sponge portion, the opposite side being a mirror image;

FIG. 10 is a top plan of the base portion of FIG. 7; and,

FIG. 11 is a bottom plan view of FIG. 7.
